UNITED STATES PATENT OFFICE.

WILLIAM GETHMANN AND J. LOUIS GETHMANN, OF GLADBROOK, IOWA.

HALTER.

SPECIFICATION forming part of Letters Patent No. 371,754, dated October 18, 1887.

Application filed February 18, 1887. Serial No. 228,096. (No model.)

To all whom it may concern:

Be it known that we, WILLIAM GETHMANN and J. LOUIS GETHMANN, citizens of the United States, residing at Gladbrook, in the county 5 of Tama, State of Iowa, have invented certain new and useful Improvements in Halters, of which the following is a specification, reference being had therein to the accompanying drawings.

10 The object of this invention is to provide a rope halter for horses that may be readily adjusted to the head of any horse, the rope of which may be easily replaced when worn, and to obviate splicing or knotting the rope where 15 joints are formed.

Other objects and advantages of the invention will appear in the following description, and the novel features thereof will be particularly pointed out in the claims.

20 Referring to the drawings, Figure 1 represents a halter embodying our invention in position upon a horse. Fig. 2 is a detail in perspective of a novel coupling for connecting the crown-strap, throat-latch, and cheek-strap.

25 Fig. 3 is a perspective of the means employed for connecting the ends of the halter end of the hitching strap. Fig. 4 is a similar view showing the means employed for connecting the ends of the rope with each 30 other. Fig. 5 is a detail in perspective showing means for connecting the hitching-strap to the halter.

Like letters indicate like parts in all the figures.

35 In carrying out our invention we employ a leather or other strap for the crown and nose-band A B of the halter, at the ends of which are formed the usual loops, A' B', for the reception of the rope composing the remainder 40 of the halter. In this instance, however, we do not pass the rope directly through the loops A' B', but provide for this purpose a malleable cast-iron coupling, C, for the crown-strap, and a similarly cast and shaped coupling 45 for the nose-band.

Referring more particularly to Fig. 2 of the drawings, which is a perspective in detail of the casting C, it will be seen that it consists of curved rope-securing bail portion C', adapted 50 to rest within the loops A' B', which bail is

provided with the lips C² and downwardly-depending arms C³, at the end of one of which is formed the curved loop C⁴, and at the end of the other is formed a straight loop, C⁵, through which the rope is passed in forming the halter. 55 A strengthening bar or brace, C⁶, connects these arms and prevents their compression by the tension of the rope.

As before stated, the rope-coupling castings are mounted in each of the loops A' B', but 60 their position is reversed—that is to say, the curved loops of the ones mounted in the crown-strap point toward the nose of the animal to throw the rope forward, where it forms the cheek strap, and the ones on the nose-band 65 point in an opposite direction for the same purpose. The rope, after having been passed through the couplings described, and in the manner specified, to form the cheek-straps D, throat-latch E, and chin-strap F, the ends are 70 connected in a manner and by a device which we will now proceed to describe. It consists of a truncated cone-shaped loop or socket, G, at the larger end of which is formed a hook, G', adapted to take into the usual hitching-ring, 75 G², mounted on the chin-strap. The ends of the rope are passed into the socket G. A wedge-shaped key, G³, grooved upon opposite sides, as at G⁴, is inserted within the socket G between the ends of the rope, thus securely 80 fastening them in the socket.

From the above it is apparent that to readjust the halter for a different-size head, or to provide new ropes, it is only necessary to drive the wedge out of the socket, when the result 85 may be consummated. A somewhat similar socket to the one just described is employed to connect the end of the hitching-rope H with the hitching-ring G², as clearly shown in Fig. 5, the only difference being that by reason of 90 only one rope having to be secured the wedge G³ is grooved upon one side only and curved on its opposite side, and the socket G is designed for the rope end.

Various means for preventing the rope from 95 slipping in the couplings may be provided. Referring to Fig. 2, it will be seen that we have provided spurs C⁷, adapted to project into the rope, and also an aperture, C⁸, through which and the rope an ordinary bolt, C⁹, (see dotted 100

lines,) may be passed. If desired, however, the casting being malleable, the lips C² may be turned and clamped upon the rope. The main portion of the bail may be tubular throughout its entire length, or tubular at the ends only, as shown by dotted lines C¹⁰, into which a wedge, C¹¹, may be driven.

Having described our invention and its operation, what we claim is--

- 10 1. In a rope halter, a malleable coupling for the purpose described, comprising a rope-receiving bail, the depending arms of which are provided with loops at their ends and with a connecting brace or bar, substantially as specified.
- 15 2. In a rope halter, a malleable coupling for the purpose described, comprising a curved semicircular rope-receiving bail, with depending arms which have tubular loops at their ends, one of which loops is straight and the other curved outwardly, as and for the purpose described.

3. In a rope halter, a coupling for connecting the ends thereof, comprising a rope-securing socket having a hook, and a wedge having 25 opposite concave sides, substantially as specified.

4. The combination of the straps A and B, having loops A' B', with the couplings C, constructed as described, and the ropes D and F, 30 substantially as specified.

5. The combination of the straps A and B, the couplings C, constructed as described, with the ropes D, E, and F, socket G, rope H, and ring G², substantially as specified. 35

In testimony whereof we affix our signatures in presence of two witnesses.

WILLIAM GETHMANN.
